METHOD OF MAKING SHOES

Karl A. Stritter, Nahant, Mass., assignor to United
Shoe Machinery Corporation, Flemington, N. J.,
a corporation of New Jersey

Application July 14, 1945, Serial No. 605,068

7 Claims. (Cl. 12—142)

1

This invention relates to methods of making shoes and particularly shoes having open rear ends and heels which are trimmed after attachment thereto such, for example, as leather heels.

In shoes of the open-heel type, the rear part of the shoe upper may be entirely lacking or may consist only of an ankle strap or a strap extending about the rear end of the foot above the bulge of the heel. The heel-seat portion of the insole of such shoes is left without support, that is, without anything to hold it against the bottom of the last. This condition renders difficult not only the location of the shoe and heel relatively to each other and the attachment of the heel, but also, after an outsole and an untrimmed heel are attached to such a shoe, the trimming of the heel and the other operations, such as scouring and finishing, are rendered especially difficult because the pressure of the heel against the trimming cutter or the other finishing tools causes the soles to bend at the breast line and the insole to separate from the last bottom, accurate trimming and finishing of the heel being thus rendered difficult or impossible.

Objects of this invention are to provide a method by which an untrimmed heel on a shoe having an open heel end may be accurately located, attached, trimmed and finished, and to improve the quality of this type of shoe.

In practising the method of the present invention, the quarter lining of the shoe is made to extend about the rear end of the last and is of sufficient extent heightwise to enable its lower portion to be lasted over the heel-seat portion of the insole. The lower portion of the lining is then lasted over the heel-seat of the insole in the usual manner, an outsole and untrimmed heel attached to the shoe, the heel trimmed, scoured and finished while the insole is held tightly against the last by the lasted lining and then a portion of the lining is utilized to cover the edge face and marginal portion of the insole about the heel-seat.

In case the upper at the rear end of the shoe consists merely of a strap extending about the rear end of the foot above the bulge of the heel, the upper portion of the quarter lining will be utilized to line the strap and, of course, the right or finished side of the lining will be exposed inside the shoe and the unfinished side of the lining exposed in the region of the open heel. Therefore, the portion used to cover the edge face and marginal portions of the insole will be wrong side out. This construction, however, would be acceptable if the lining were of reversible material, that is, if either side of the material were

10 suitable for exposure in the finished shoe. Such materials, however, are not usually available and, accordingly, as a further aspect of the method, the quarter lining is made to extend toward the sole only part way across the heel opening and has secured thereto a piece of material with its finished side out and of a quality to provide a suitable cover for the rear end of the insole.

15 This pieced quarter lining or extension of the strap lining is lasted over the heel-seat portion of the insole, thus providing in effect a complete upper in the rear part of the shoe. Then, after an outsole and an untrimmed heel are attached and the heel trimmed and finished, including slugging of the top-lift if desired, the quarter lining is severed along a line substantially parallel to the plane of the heel and spaced heightwise of the heel of the shoe therefrom sufficiently to provide enough of that portion of the lining material which is right side out to cover the edge face and marginal portion of the inner face of the insole. This lining material is then laid over the inner face of the insole and attached thereto by cement, its marginal portion being pinked if necessary to cause it to lie flat without wrinkles. The remainder of the lining material extending from the strap (if a strap is used) into the heel opening is trimmed flush with the lower edge of the strap, resulting in a finished open-heel shoe with a properly located, attached, trimmed and finished heel.

20 In the drawing,

25 Fig. 1 is a perspective view of the rear portion of a shoe being made in accordance with the present invention and showing a complete quarter lining lasted over the heel-seat portion of an insole;

30 Fig. 2 is a similar view of a shoe after a sole and an untrimmed heel have been attached to the shoe and the heel partially trimmed;

35 Fig. 3 is a perspective view of the shoe after the heel has been trimmed and finished, the last removed and the upper portion of the quarter lining trimmed away; and

40 Fig. 4 is a similar view showing the utilization of the lower portion of a quarter lining as a cover for the heel-seat portion of the insole.

45 In carrying out the method of the present invention, as herein illustrated, an upper 10 is prepared as shown in Fig. 1, mounted upon a last 12, and the shank and forepart lasted in any usual manner, a shoe of welt construction being indicated in the drawing. In the finished shoe the rear part of the upper may consist only of a strap 14 extending about the heel end of the last

above the rearward bulge of the heel. In this case the upper and lower edges of the strap are finished and the strap has a lining 16 of usual quarter lining material such as kid leather with its finished face inside of the strap and secured thereto by lines of stitching 18 as usual. By the present method the strap lining 16 is extended downwardly into what will eventually be the opening at the heel end of the shoe. To the lower portion of the lining 16 is secured in any suitable manner, for example by zigzag stitches 20 as shown, a piece of material 22 with its finished side out and suitable for binding the edge portion of the rear part of an insole 24 which is to be exposed in the heel opening. This piece 22 is wide enough so that it can be lasted over the heel-seat portion of the insole 24 and secured thereto in any usual manner, for example by tacks 26 as shown in Fig. 1. The pieces 16 and 22 together constitute a complete quarter lining the lower marginal portion of which can be worked over and secured to the outer face of the insole, thus holding the rear portion of the shoe tightly against the bottom of the last 12, the condition at the rear end of the shoe (Fig. 1) being thus rendered similar to that of a shoe having a complete upper with the heel-seat lasted in the usual manner. After attachment of an outsole 28 in any usual manner, the location and attachment of an untrimmed heel 30, which are the next steps, are facilitated by having the insole thus held tightly in place against the last. After attachment of the heel, it is trimmed, scoured and finished and, if desired, slugs 32 may be inserted through the top-lift. These operations can be carried out with the same facility as they are upon a shoe having a complete upper at the heel end.

After the usual finishing operations on the heel and sole are completed, the last is removed and the part 22 of the lining cut below its attachment to the piece 16, for example along the dotted line 34 in Fig. 2 parallel to the plane of the insole and located above it sufficiently to provide a cover for the edge face and upper marginal portion of the insole. The exposed portion of the lining 16 is trimmed away flush with the lower edge of the strap 14, as shown in Fig. 3. Cement is then applied to the marginal portion of the insole and to the inner face of the upstanding portion of the piece 22. This portion is then laid over upon the cemented insole and may be pinned as shown at 36 if desired to enable it to lie flat upon the insole. A heel pad 38 may be applied over at least a portion of the insole.

The strap lining 16 may, of course, extend far enough to be lasted over the insole, but in that case the lining material should be finished on its outer as well as its inner side. This method may be followed where a reversible lining material is available one side of which is suitable for exposure inside and the other for exposure outside the shoe. However, under usual conditions it will be more desirable and convenient to employ a pieced quarter lining the upper part of which has an inside finish and the lower part an outside finish, as above described. If the shoe has no strap at the heel end or only a high ankle strap, the quarter lining may be extended to form a closure for the rear end of the last and may be pieced or not, depending on the materials used. In this case, after the lining is lasted and the heel attached, trimmed and finished, the lining will be cut at the proper distance above the insole and its lower portion utilized to cover the heel

end of the insole, as above described. The remainder of the quarter lining which extends rearwardly beyond the shoe upper will be trimmed away to provide a shoe having a completely open heel end.

Having thus described my invention, what I claim as new and desire to secure by Letters Patent of the United States is:

1. That improvement in methods of making shoes which comprises providing an open-heel upper with a complete quarter lining, assembling the upper on a last with an insole, lasting said lining to the heel-seat of the insole, attaching a heel to the shoe, trimming and finishing the heel while the insole is held in place on the last bottom by the lasted quarter lining, and utilizing a portion of the quarter lining to cover the edge face of the insole where it would otherwise be exposed in the finished shoe.
2. That improvement in methods of making shoes which comprises attaching to an extended strap lining material suitable for covering the rear end of an insole, assembling the upper and an insole on a last, lasting the lining over the heel-seat of the insole, attaching a sole and an untrimmed heel to the shoe, trimming the heel, removing a portion of the lining below the strap and above a line parallel to the insole and spaced above it to provide material to be laid over the marginal portion of the inner face of the insole, and laying said material over and securing it to the insole.
3. That improvement in methods of making open-heel shoes which comprises providing a quarter lining, attaching to the quarter lining a piece of material suitable for covering the rear end of an insole, assembling the upper and an insole on a last, lasting the lining over the heel-seat of the insole, attaching a sole and an untrimmed heel to the shoe, trimming the heel, removing the lining above a line parallel to the insole and spaced heightwise from it to provide material to be laid over the marginal portion of the inner face of the insole, and laying said material over and securing it to the insole.
4. That improvement in methods of making open-heel shoes which consists in providing an upper having a complete quarter lining, mounting the upper on a last, lasting the shank and forepart in the usual manner, lasting the quarter lining only over the heel-seat of the insole and securing it thereto, attaching an outsole and an untrimmed heel to the shoe, trimming and finishing the heel while the insole is held against the last by the quarter lining, and utilizing a portion of the quarter lining to cover the edge face and inner marginal portion of the insole.
5. That improvement in methods of making shoes which consists in providing an upper having a heel strap only about the rear end of the shoe, providing a complete quarter lining as a lining for the strap, mounting the upper on a last, lasting the shank and forepart in the usual manner, lasting the quarter lining only over the heel-seat of the insole and securing it thereto, attaching an outsole and an untrimmed heel to the shoe, trimming and finishing the heel while the insole is held against the last by the lasted quarter lining, and utilizing a portion of the quarter lining to cover the edge face and inner marginal portion of the insole, the remainder of the lining being trimmed flush with the lower edge of the strap.
6. That improvement in methods of making

shoes which consists in providing an upper having an open heel end with a strap to extend around the foot above the bulge of the heel and a two-piece quarter lining the upper portion of which has an inside finish forming a lining for the strap and the lower portion an outside finish suitable for covering the heel end of the insole, mounting the upper upon a last, lasting the quarter lining over the heel-seat of the insole, attaching an outsole and an untrimmed heel to the shoe, trimming the heel while the quarter lining is intact, then severing the quarter lining along a line parallel to the heel-seat and spaced therefrom heightwise of the shoe, trimming the upper portion of the quarter lining flush with the lower edge of the strap, and laying the lower portion of the quarter lining over the marginal portion

of the inner face of the insole and securing it thereto.

7. That improvement in methods of making shoes which consists in providing an upper having a heel strap only about the rear end of the shoe, providing a complete quarter lining as a lining for the strap, mounting the upper on a last, lasting the shank and forepart in the usual manner, lasting the quarter lining only over the heel-seat of the insole and securing it thereto, attaching an outsole and an untrimmed heel to the shoe, trimming and finishing the heel while the insole is held against the last by the lasted quarter lining, and trimming the quarter lining flush with the lower edge of the strap.
